UNITED STATES PATENT OFFICE

130,748

DESIGN FOR A TOASTER

Jean O. Reinecke, Oak Park, and James F. Barnes,
Chicago, Ill., assignors to McGraw Electric
Company, Elgin, Ill., a corporation of Delaware

Application April 25, 1941, Serial No. 100,622

Term of patent 7 years

To all whom it may concern:

Be it known that we, Jean O. Reinecke and James F. Barnes, citizens of the United States and residents, respectively, of the village of Oak Park, county of Cook, State of Illinois, and of the city of Chicago, county of Cook, State of Illinois, have invented a new, original, and ornamental Design for a Toaster, of which the following is a specification, reference being had to the accompanying drawing, forming part thereof, in which:

Fig. 1 is a top plan view of a toaster, showing our new design.

Fig. 2 is a side elevational view thereof, and Fig. 3 is a front elevational view thereof.

The rear of the toaster is substantially the same as the front except for the absence of the slot and the presence of a bushing.

We claim:

The ornamental design for a toaster, substantially as shown and described.

JEAN O. REINECKE.
JAMES F. BARNES.
